UNITED STATES PATENT OFFICE

FRANK M. VOGAN, OF CANTON, OHIO, ASSIGNOR TO THE REEVES MANUFACTURING COMPANY, OF DOVER, OHIO, A CORPORATION OF OHIO

DESIGN FOR A WASHBOARD

Application filed March 1, 1932. Serial No. 43,047. Term of patent 14 years.

To all whom it may concern:

Be it known that I, FRANK M. VOGAN, a citizen of the United States, residing at Canton, in the county of Stark and State of Ohio, have invented a new, original, and ornamental Design for Washboard, of which the following is a specification, reference being had to the accompanying drawings, forming part hereof.

Fig. 2, a longitudinal sectional view of the washboard shown in Fig. 1.

I claim:

The ornamental design for a washboard, as shown.

FRANK M. VOGAN.
